UNITED STATES PATENT OFFICE.

FRANK WETZEL AND GEORGE LANGEN, OF CINCINNATI, OHIO, ASSIGNORS TO THE CINCINNATI PLANER COMPANY, OF CINCINNATI, OHIO, A CORPORATION OF OHIO.

DESIGN FOR A THERAPEUTIC LAMP.

Application filed June 13, 1928. Serial No. 27,114. Term of patent 14 years.

To all whom it may concern:

Be it known that we, FRANK WETZEL and GEORGE LANGEN, citizens of the United States, residing at Cincinnati, in the county of Hamilton and State of Ohio, have invented a new, original, and ornamental Design for Therapeutic Lamp, of which the following is a specification, reference being had to the accompanying drawing, forming part thereof.

In the drawing:

The figure is a perspective view of the lamp, showing our new design.

We claim:

The ornamental design for a therapeutic lamp substantially as shown.

FRANK WETZEL.
GEORGE LANGEN.
